UNITED STATES PATENT OFFICE.

LEO A. HENTER, OF HOT SPRINGS, MONTANA.

COMB AND CLIP.

Application filed March 17, 1924. Serial No. 699,907.

To all whom it may concern: Be it known that I, LEO A. HENTER, a citizen of the United States, residing at Hot Springs, in the county of Sanders and State of Montana, have invented certain new and useful Improvements in a Comb and Clip, of which the following is a specification.

This invention relates to improvements in combs, and more particularly to means to facilitate attachment thereof to the wearing apparel of a person.

The primary object of this invention is the provision of improvements in combs and attaching clips thereof, by means of which the comb may be connected within the pocket of a garment of a person so that the comb is hidden within the pocket, with only a small portion of the attaching clip shown. A further and important object of this invention is the provision of a novel spring clip and means cooperating therewith for connecting the article with the clip supports in a secure and non-movable manner with respect to a flap of a pocket or the like.

A further and important object of this invention is the provision of a novel comb and its attaching clip which are cooperably associated with each other and with a novel type of case within which the comb may be placed, so that the comb and case may be placed within the pocket of a person in a hidden manner.

A further and important object of this invention is the provision of a novel detachable clip for combs or the like, which is of novel formation in that the article which it is adapted to support may be hidden within a pocket, and yet attached to the flap of a pocket.

Other objects and advantages of this invention will be apparent during the course of the following detailed description.

In the accompanying drawings, forming a part of this specification, and wherein similar reference characters designate corresponding parts throughout the several views.

Figure 1 is a front elevation of a pocket of a garment, showing the relation in which the comb may be hidden within the pocket and connected to the flap of the pocket by means of the improved attaching clip.

Figure 2 is a cross sectional view taken through the pocket illustrated in Figure 1, showing the relation of the comb and attaching clip therein.

Figure 3 is a fragmentary view of a pocket of a garment showing the relation in which the improved comb and clip may be supported therein when the comb is received within a special case.

Figure 4 is a cross sectional view taken through the case and pocket structure showing the relation of the case, comb, and attaching clip with respect to the pocket.

Figure 5 is a cross sectional view taken through the improved comb and attaching clip, showing the relation of these parts.

Figure 6 is a fragmentary side elevation of the comb with the improved attaching clip associated therewith.

Figure 7 is a cross sectional view taken through a pocket showing the relation of a comb and a modified form of attaching clip which may be used in connection therewith for supporting the same in attached relation to the flap of the pocket.

Figure 8 is a cross sectional view showing the modified form of clip and comb.

Figure 9 is a side elevation of the comb and clip illustrated Figure 7.

Figure 10 is a fragmentary view of an end of the comb showing the construction thereof for cooperation in receiving the modified clip.

In the drawings, wherein for the purpose of illustration are shown the forms of this invention, the letter A may generally designate the preferred type of comb with which the improved clip B may be associated. A comb C may also be used for the detachable reception of the novel modified form of clip D.

The comb A is of any approved construction, including the back strip 15 outwardly of which the spaced teeth 16 are formed. The clip B is connected adjacent an end of the comb A; this clip including a flat straight attaching strip 20, the arcuate bight portion 21; and the resilient or spring tongue 23 connected to the attaching leg or strip 20 by the bight portion 21, the spring tongue 23 preferably having a slope toward the plane of the attaching leg 20. The tongue 23 at its free end is preferably provided with a ball head 25.

As to the attachment of the clip B upon the comb A, the leg 20 is secured in abutting relation at a side of the comb back 15, by means of rivets 27 and 28, so that the leg 20 extends slightly above the top edge 28a of the comb A; and the arcuate bight portion

21 extends upwardly and over the top edge 28^a of the comb A in a spaced relation therewith, so that the resilient tongue 23 depends along the opposite side of the comb A in a 5 slightly sloping relation towards said comb. The rivets 27 and 28 are preferably provided with heads 30 and 31 respectively, at the side of the comb along which the tongue 23 extends; the tongue ball 25 being disposed 10 in a novel cooperating relation between the heads 30 and 31.

A comb case E may be supplied for receiving the comb A therein; this comb case 15 being of any approved material and formation, being entirely open at its upper end, and in the front wall 35 thereof preferably having a slot 36 extending downwardly from the top edge thereof, and along which slot the heads 30 and 31 of the rivets, and 20 the ball head 25 of the tongue 23 may slide to permit proper insertion of the comb within the case E.

As to the application of the comb and its case within the pocket of a garment F, the 25 comb and its case are slipped within the pocket 38 so that the comb and case are entirely secreted within the pocket behind the front flap 39 of the pocket. Due to the spaced relation of the arcuate bight portion 21 of 30 the attaching clip this arcuate bight portion may extend over the top edge of the flap 39 so that the spring tongue 23 lies exterior of the pocket flap 39. The material of the flap 39 will, of course, be clamped between heads 30 and 31, and the ball 25 of 35 the spring tongue 23, will force the material of the pocket into a crimped relation between the heads 30 and 31 incident to spring action of the tongue 23, and as is illustrated 40 in Figure 4 of the drawings. The comb and the case are entirely secreted within the pocket, and the only visible portion of the device is the spring tongue 23. The comb may be used without the case, as is illustrated 45 in the cross sectional view in Figure 2 of the drawings, and in this instance the comb is also invisible within the pocket; the upper edge of the flap 39 fitting into the 50 space in the arcuate portion 21 between the same and top edge 28^a of the comb A.

Referring to the modified form of this invention the comb C is of any approved construction, including the back 40 outwardly of which the spaced teeth 41 are formed. 55 Adjacent an end edge 42 of the comb C, and inwardly of a side of the back 40 a pair of recesses 43 and 44 are formed, which are arranged in alignment with the length of the back 40.

60 The clip D is of a novel construction, and consists of a substantially U-shaped attaching portion 48, and a spring tongue 49 connected to the portion 48 by means of a bight 50.

65 The U-shaped attaching portion 48 prefer-

ably comprises the side legs 52 and 53, which may be of equal length, and connected by a bight 54. The bight portion 50 which connects the tongue 49 to the portion 48 is attached, as at 56, to the portion 48 contiguous 70 with the leg 52, and so that the bight portion 50 extends upwardly in a spaced relation with the bight portion 54 of the attaching portion 48. The tongue 49 extends downwardly along, in spaced relation with 75 the leg 53 of the attaching portion 48, and slopes inwardly, as at 57, adjacent its free end, and at its free end thereof is provided with a ball head 58.

In the application of the improved clip D 80 upon the comb C the attaching portion 48 is slipped over the end of the comb C so that the spaced lugs 59 and 60, which are formed inwardly in projecting relation on the leg 52, engage in detachable manner in the recesses 43 and 44 of the comb C. The legs 52 and 53 of the attaching portion 48, of course, grip the back of the comb in a secure clamping relation, and the bight portion 50 of the clip D extends upwardly 85 above the top edge of the comb; the spring tongue 49 extending downwardly along a side of the comb with its ball 58 engaging the side of the comb, substantially as is illustrated in Figure 8 of the drawings. 90

The application of the comb and clip C and D respectively within the pocket F is obvious. The comb C is entirely hidden within the pocket 38; the upper edge of the 95 pocket flap 39 fitting into the space within the arcuate bight portion 50 of the clip D, and exterior of the pocket the only portion visible is the spring tongue 49.

From the foregoing description of this 100 invention it is apparent that a novel comb and its attaching clip has been provided which enables the comb to be supported in a compact relation within the pocket and invisible therein. The clips cooperate in a 105 novel relation with the comb to most effectively maintain the comb in an attached relation to the flap of the pocket.

Various changes in the shape, size, and arrangement of parts may be made to the 110 forms of the invention herein shown and described, without departing from the spirit of the invention or the scope of the claims.

I claim:

1. In a device of the class described the 115 combination of a comb, and a U-shaped clasp secured to the comb and comprising an attaching leg secured to the comb by means of rivets which at the opposite side of the comb from the side to which the leg is secured provide a pair of spaced projecting heads, a bight portion extending upwardly 120 of the end of the comb in an arcuate relation thereover, and a resilient tongue extending along the opposite side of the comb 125 from that side adjacent which the attach-

ing leg is secured, said tongue providing at its free end a ball shaped head extending into the space between the projecting heads of said rivets.

5. 2. In a device of the class described the combination with an article to be supported, of a U-shaped clip, rivets securing the U-shaped clip to the article and providing spaced heads projecting from a side of the article, said clip providing a resilient tongue with a head portion at the free end thereof normally urged into the space between the heads of said rivets.

10. 3. In a device of the class described the combination of a casing providing a slot inwardly of the top edge thereof, a comb for disposition within said casing, an attaching clip, means securing the attaching clip to the comb and providing a pair of spaced projections at a side of said comb which are adapted to ride downwardly within the slot of said casing when the comb is disposed within the casing, and an

attaching clip providing a resilient tongue with an enlarged head at the free end thereof normally urged into the space between the projecting heads of said rivets.

15. 4. In a device of the class described the combination with an article including an end edge, of a substantially U-shaped clip 30 including an attaching leg, an upper bight portion, and a resilient tongue, means securing said attaching leg at a side surface of said article adjacent said end edge of the article so that the said attaching leg extends 35 upwardly above the end edge of the article with the bight portion of said clip extending in spaced relation over the end edge of the article to provide a space between said end edge of the article and the under surface of the bight portion of the U-shaped clip, said resilient tongue extending downwardly in spaced relation at the opposite side of said article from that side to which said attaching leg is affixed.

LEO A. HENTER.
